UNITED STATES PATENT OFFICE.

MARVIN B. DAVIS, OF KANSAS CITY, MISSOURI, ASSIGNOR TO GEORGE KRELL, OF SAPULPA, OKLAHOMA.

CLAMPING SPIDER.

Application filed April 30, 1926. Serial No. 105,741.

My invention relates to spiders used in connection with oil well apparatus and more particularly to a spider that is provided with means for clamping a casing or tubing to hold the same from downward movement relative thereto.

It is a purpose of my invention to provide a device of the above mentioned character in which bell crank levers are utilized for supporting the clamping jaws, said bell crank levers being connected with a base member and with each other in such a manner that when the jaws as a whole are moved upwardly they will separate and when the same are moved downwardly they will move toward each other to clamp a member therebetween. Thus the tendency toward downward movement of the casing or other member to be held by the jaws, will tend to cause the jaws to exert a firmer grip on the member engaged thereby. The device is preferably so constructed that the same can be readily engaged around and removed from embracing relation to a casing or other member with which the same is associated.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a perspective view of my improved clamping spider, showing portions of a casing head associated therewith.

Fig. 2 is a view partly in plan and partly in horizontal section of my improved clamping spider, and

Fig. 3 is a vertical, sectional view thereof.

Referring in detail to the drawings:

My improved spider comprises a base member 10 that is provided with a U shaped opening or slot 11 so that the same can be readily engaged around a casing or tubing 12, said base member being further preferably provided with depending ears 13 having the set screws 14 for connecting the same with a flange 15 on the casing head 16. The base member is further preferably provided with pairs of upstanding ears 17 which carry

the transverse shafts 18 upon which are mounted to pivot thereon the links 19. The opposite ends of the links 19 are provided with transversely extending shafts or pivot pins 20 upon which the lower ends of the bell crank levers 21 are mounted, thereby providing a floating mounting for the lever 21 in that the lever may have both vertical and lateral adjustment under the conditions presently described. The bell crank levers 21 are provided with outwardly extending pivot projections 22 that seat within the sockets 23 provided on the links of fixed length 24 connecting opposite pairs of said bell crank levers. Hollow bosses 25 are provided on the links 24 at the sockets 23, through which the screws 26 extend for securing the links 24 detachably to the bell crank levers. The bell crank levers are further provided with transversely extending pivot members 27 extending substantially parallel to the pivot members 18 and 20 and connecting the bell crank levers in pairs, the pivot members 27 being offset from the pivot projections 22 as will be clearly seen from Figs. 2 and 3.

The pivot members 27 are provided with enlargements 28 forming bearing portions receiving the bearings 29 provided on the jaws 30. The jaws 30 are preferably channel-shaped and receive the gripping members 31 therein, the gripping members being adapted to pivot slightly on the pivots 32 and 33 provided in the ears 34 and the detachable clips or ears 35 on the jaws 30. There is preferably a pair of gripping members or slips 31 associated with each of the jaws 30, as will be clear from Fig. 2. The gripping members 31 are preferably provided with gripping teeth 36 that will hold the casing or other tubular member 12 from downward movement relative to the jaws.

Mounted on one of the ears 17 is an operating lever 37, the same being pivotally mounted on one of the members 18 and having an upwardly extending arm 39 to which the link 40 is pivoted by means of the member 41. The link 40 is further pivotally connected with one of the links 24 by means of the pivot member 42.

In operation the weight of the tubular member 12 will tend to move the jaws as a whole downwardly, which will tend to swing the pivots 27 around the pivots 22 in a direction so that said pivots 27 move toward each other, thus causing the jaws 30 to move to

ward each other to more firmly grip the tubing with the gripping members 31. When it is desired to release the gripping members 31 from the tubing or casing 12, the lever 37 is actuated to move the arm 39 thereof in a clockwise direction, whereupon the link 40 is moved outwardly, carrying one of the links 24 and thus the entire structure including the pivot members 27 therewith, causing the members 27 to rotate around the members 22 so as to move away from each other, whereupon the jaws 30 will separate, disengaging the gripping members from the tubular member 12.

15 When it is desired to place the spider in position around the tubing or casing, or to remove the same therefrom, one of the links 24 is detached and the jaws 30 are spread apart. The spider is placed in position by moving the same laterally around the pipe or tube through one side of the separated jaws 30 and through the open end of the U-shaped slot 11. In removing the spider the same is again moved off the pipe or tube through the open end of the slot and between the sides of the separated jaws on that side of the device on which the open end of the slot lies.

30 What I claim and desire to secure by Letters Patent is:—

1. A device of the character described comprising a base, spaced link mountings on said base, links pivotally suspended from said mountings, crank levers pivotally mounted on said links, jaws pivotally mounted on said crank levers, and a rigid link pivotally connected with the crank levers for the respective jaws on axes eccentric to those of the jaw mountings and connecting the jaws to effect closure of the jaws when the jaws are moved transversely of the link in one direction.

45 2. A device of the character described comprising a base, spaced link mountings on said base, links pivotally suspended from said mountings, crank levers pivotally mounted on said links, jaws pivotally mounted on said

crank levers, a rigid link pivotally connected with the crank levers for the respective jaws on axes eccentric to those of the jaw mountings and connecting the jaws to effect closure of the jaws when the jaws are moved transversely of the link in one direction, and an operating lever pivoted on the base and connected with said link for moving the link in the other direction to open the jaws.

50 3. In a device of the character described, a base, slotted to receive an object to be clamped and having a pair of upstanding ears at each side of the slot, a shaft carried by each pair of ears, a pair of links pivotally suspended from each shaft, a pin carried by each pair of links, a pair of crank levers carried by each of said pins, opposed jaws pivotally mounted on respective pairs of crank levers, and rigid links at opposite sides of the jaws, pivotally connected with opposed jaw levers on axes eccentric to those of the jaw mountings, whereby movement of the jaws transversely of the connecting links in one direction will tend to shift the levers and their mountings and close the jaws.

55 4. In a device of the character described, a base, slotted to receive an object to be clamped and having a pair of upstanding ears at each side of the slot, a shaft carried by each pair of ears, a pair of links pivotally suspended from each shaft, a pin carried by each pair of links, a pair of crank levers carried by each of said pins, opposed jaws pivotally mounted on respective pairs of crank levers, rigid links at opposite sides of the jaws, pivotally connected with opposed jaw crank levers on axes eccentric to those of the jaw mountings, whereby movement of the jaws transversely of the connecting links in one direction will tend to shift the crank levers and their mountings and close the jaws, and an operating lever on said base 60 flexibly connected with one of said connecting links for moving the jaw in the opposite direction to open the jaws.

70 In testimony whereof I affix my signature.
75 MARVIN B. DAVIS.
